UNITED STATES PATENT OFFICE.

ERNEST V. JOHNSON, OF CHICAGO, ILLINOIS.

METHOD OF DISTRIBUTING BUILDING MATERIALS.

1,111,071.

Specification of Letters Patent. Patented Sept. 22, 1914.

Application filed December 2, 1912. Serial No. 734,431.

To all whom it may concern:

Be it known that I, ERNEST V. JOHNSON, a citizen of the United States, residing in Chicago, in the county of Cook and State 5 of Illinois, have invented a new and useful Improvement in Methods of Distributing Building Materials, of which the following is a specification.

This invention relates to an improved 10 method of distributing building materials of fireproof buildings during the process of erection.

An object of the invention is to devise a method of distributing building materials, 15 such as tile, mortar, cement or grouting over the entire area of each floor of steel skeleton or frame buildings or reinforced concrete buildings as the construction progresses, which will minimize, as far as possible, 20 the cost of the labor therefor, the time required for handling the materials, and which will facilitate the work of all the laborers.

The invention furthermore consists in the 25 improvement in the steps and the novel combinations of the steps hereinafter described or claimed.

As is well known, fireproof buildings are now generally constructed by erecting 30 the skeleton framework of steel or reinforced concrete columns, girders and beams, floor by floor, and as fast as one floor of the skeleton is finished, the false work or centering is put in place for said floor, and then 35 the fireproofing tile are distributed and roughly stacked in place over the entire floor area on the centering, after which the tile-layers come along and apply the cement or grouting to the tile and place the latter in 40 permanent position.

So far as I am aware, it has hitherto been the universal practice in distributing tile and other building material over each floor, to employ the following method and apparatus: A pair of small freight elevators are arranged at each advantageous point of distribution in the building, in the case of small buildings, one pair being generally used, and in larger buildings, two pairs, one pair at 45 each end. Each pair of elevators is so arranged that as one goes up, the other comes down, the travel of the elevators being changed from time to time as floor after floor 50 of the building is constructed, so that the upper going elevator will always stop at the level of the last completed floor and on which the

distribution of the tile or other building materials is taking place, and the downcoming elevator will always stop at the ground level, where the tile are received from wagons. 60 Each of these elevators, as hitherto constructed, is only large enough to carry a single wheelbarrow at a time, and when the elevators are brought to rest at their extreme upper and lower positions, laborers 65 replace an empty wheelbarrow on the elevator at the bottom with one filled with tile, and a filled wheelbarrow on the elevator at the top with an empty one, this operation being repeated as the elevators 70 are alternately raised and lowered. The wheelbarrows which have been used in this work are necessarily limited in capacity, on account of the fact that the laborers in moving the same have to support a major 75 part of the load, and such capacity, in the case of large size fireproofing tile, is limited to four pieces, so that, although the elevators are operated at high speed, yet the aggregate time consumed in delivering all the tile 80 required on any one floor, four at a time, is relatively great. It has always been customary to have the wheelbarrows delivered by the elevators at a level flush with the temporary wheelbarrow plank platform, which, 85 so far as I am aware, has always been loosely laid directly on top of the girders and beams. These planks must be shifted from time to time as the laborers distribute the tile over the different parts of the floor, 90 since the tile are of necessity always dropped from the hand onto the centering or false work adjacent the wheelbarrow platform and as soon as one space is filled, the distributor delivers the tile to the next space. 95 After the tile have thus been delivered, the stackers arrange the same roughly in rows ready for the tile-layers to apply the cement or grouting. In this connection, it will be observed that neither the stackers nor the 100 tile-layers can complete their part of the work in any space so long as the wheelbarrow platform is in position thereover, because the latter, resting directly on top of the beams, prevents the tile from being 105 properly handled therebeneath, as the height of fireproofing tile generally approximates that of the beams and girders themselves, so that in the space between the false work or centering and the plank platform sufficient clearance is never provided 110 for putting the tile in position, nor for per-

mitting the stackers or layers themselves to work thereunder. The foregoing outlines, briefly, the method and apparatus hitherto used in the erection of fireproof buildings, 5 as observed by me during the many years in which I have been actively engaged in constructing fireproof buildings, and it will be apparent that with the practice above outlined, the speed with which the materials 10 are distributed is limited, much time is wasted in continually having to shift the wheelbarrow plank platforms and the stackers and tile-layers are hampered and delayed in their work, so that all of these factors 15 combine to increase the cost of construction.

In order to do away with all the above indicated objections of the old practice employed in distributing building materials, I 20 employ the following means: Instead of using wheelbarrows adapted to carry only four tile at a time, I employ wheel trucks that can carry upward of thirty tile at a time, which a laborer can easily pull around 25 on the platform provided therefor without undue exertions or strains on his part, and without the necessity of supporting any of the weight of the load. Elevators operating in pairs, as hitherto, are also provided, but 30 the same are made large enough to carry the wheel trucks above described, and the same method of loading and unloading the elevators is employed. In this connection, it 35 will be seen that over seven times the number of tile are handled by the same number of laborers in the same time as heretofore, or, stated in another manner, only one-seventh as many laborers need be employed to distribute the same number of tile as 40 heretofore required. I also provide a platform for the trucks which, after being once placed in the most advantageous position for a floor, is never moved or changed until 45 all the tile have been distributed over that floor and operations transferred to the next higher floor. This platform, which is made wide enough for two trucks to pass each other, is rigidly secured in position on the beams and girders and is elevated to a plane 50 approximately four feet above the centering or false work, and the upgoing elevators are stopped flush with the level of this platform, so that the trucks may be run directly 55 thereonto from the elevators. The four foot space thus provided between the platform and the false work permits both the stackers and the tile layers to work all over the floor space, including that beneath the platform, without any interference in their work, even 60 while the platform is in place, so that the stacking and laying will progress as fast as the distributing can be accomplished, thus preventing the necessity for separating the gangs of laborers and having one gang on 65 one floor and another gang on another floor.

Another important result obtained by elevating the platform, as described in the foregoing, resides in the fact that it allows the laborers to distribute the tile from the platform to any place desired on the floor 70 on either side of the track by means of a shiftable gravity conveyer having its top end detachably secured to the track and its lower end resting on the false work. By using such gravity conveyers, the laborer, 75 after having pulled the truck along the platform to the desired place, merely places the tile on the gravity conveyer and as the tile slide automatically down the conveyer under the influence of gravity, the stackers 80 stand alongside, pick off the tile one by one and arrange them in proper position. This method, as will be obvious, avoids the necessity of having to shift the platform during the operations on one floor, since the 85 gravity conveyers are long enough to extend from the platform to parts of the floor farthest therefrom, and the same can be easily shifted or moved along the platform from time to time without moving or disturbing the platform, so that the laborers 90 who haul the trucks are never interrupted in their work.

By employing my method above described, I estimate that a saving of fully 95 twenty-five per cent. in the cost of labor will be effected.

In the drawing forming a part of this specification, are illustrated suitable means for carrying out my method, and in said drawing, Figure 1 is a diagrammatic plan view of one floor of a building, showing the relative positions of the elevators and platform. Fig. 2 is an enlarged, sectional view showing the elevated position of the platform and the manner of supporting the same on the beams, and showing also a wheel truck suitable for carrying thirty or more tile, and Fig. 3 is another sectional view, taken substantially at right angles to the view shown in Fig. 2, and illustrating more particularly the step of distributing the tile from the platform by means of the gravity conveyer.

In the drawing, the floor plan of a building is shown by the outline 10, and the building, of which the floor plan is illustrative, is provided with an inner court 11. Temporary elevator shafts 12 are provided at each end of the building, in each of which are operated a set of elevators 13, the same simultaneously, alternately raised and lowered. Adjacent the elevator shaft is placed a platform 14, wide enough for two trucks to pass each other, which, as shown, 120 extends entirely around the building, and is preferably located equi-distant from the inner and outer walls of the building at all points. The elevators 13 are made large enough to accommodate a wheeled truck, 125 130

such as illustrated at 15, which is adapted to carry thirty or more tile 16, and, as will be understood, the loaded trucks are placed on the elevators when the same are in their lowermost position on the ground floor. The upgoing elevator is stopped flush with the raised or elevated platform 14, so that the truck may be easily moved from the elevator to the platform, which, as shown, is supported approximately four feet above the false work or centering 17 on the I-beams 18 by supporting members 19, the latter having means 20 for rigidly connecting the same to the I-beams. After the trucks have been wheeled to a point on the platform nearest the area to which the tile are to be supplied, the laborer then places the tile one by one on a gravity conveyer 21, which may be of any well known construction, and which is detachably secured to the platform 14 so that it may be shifted from time to time as desired. The stackers standing upon the false work 17 can easily pick off the tile one by one from the gravity conveyer and arrange them roughly in position in the spaces between the beams, after which the tile-layers follow up the stackers and apply the cement or grouting. In Fig. 2, is shown roughly in outline a laborer working beneath the platform, showing how it is possible for the operations of stacking and laying to be completed without inconvenience to the laborers while the platform is still in position.

The foregoing describes the operations that take place on one floor, but, as will be obvious, as soon as one floor is completed, the platform is dismounted and placed in position on the next highest floor, and the operations repeated until the entire building is completed.

At 22 is shown a wheel truck provided with suitable means for carrying a large quantity of mortar, cement or grouting which may be distributed in large quantities to any point desired on a floor by pulling the trucks around. In this way the mortar, cement or grouting may be handled in much larger quantities than has hitherto been customary with the old wheelbarrow method, and not only is this class of material handled in larger quantities, but waste from spilling is also prevented. With the old hand wheelbarrow, it has been customary to deliver, approximately one cubic foot of mortar or cement at a time, whereas by delivering the same with a wheel truck, approximately ten times that amount may be delivered in the same time, and by the same number of laborers.

Although I have herein described what I now consider the preferred manner of carry-

ing out my process, yet it will be understood that changes and variations may be employed without departing from the spirit of 65 the invention, and all such changes and variations are contemplated as come within the scope of the claims appended hereto.

I claim:

1. The method of distributing building 70 materials during the construction of a building, which consists in providing a platform upon the frame of the building at a sufficient height above the horizontal floor beams to permit laborers to work beneath said platform, elevating a quantity of said materials 75 in a transportable carrying vehicle to said platform, moving said vehicle over said platform to adjacent appropriate points of distribution and delivering said materials 80 to said points with a shiftable gravity conveyer, substantially as specified.

2. The method of distributing building materials during the construction of a 85 building, which consists in providing a platform upon the frame of the building at a sufficient height above the floor beams to permit laborers to work under said platform, elevating a quantity of said materials 90 in a transportable carrying vehicle, moving said vehicle over said platform to adjacent appropriate points of distribution and distributing said materials said points by gravity, substantially as specified.

3. The method of distributing building 95 material during the construction of a building, which consists in providing a platform upon the frame of the building at sufficient height above the floor beams to permit laborers to work under said platform and 100 adjacent a delivery elevator shaft, loading said materials in a suitable transportable carrying vehicle, moving said vehicle on to said elevator and from said elevator to said platform, moving said vehicle along said 105 platform to appropriate points of distribution, and distributing said materials to said points by gravity, substantially as specified.

4. The method of distributing building materials during the construction of a building, which consists in providing a platform extending substantially around the walls of the building and at a sufficient height above the floor beams to permit laborers to work under said platform, elevating a quantity of 110 said materials in a transportable carrying vehicle, moving said vehicle about said platform, and distributing said material by gravity to appropriate location, substantially as specified.
